Inventor,
Anthony J. Trentacoste,
By his Attorney, *J. A. Byrne*

UNITED STATES PATENT OFFICE.

ANTHONY J. TRENTACOSTE, OF NEW YORK, N. Y., ASSIGNOR TO INNOVATION TRUNK COMPANY, A CORPORATION OF NEW YORK.

WARDROBE TRUNK.

Application filed January 10, 1928. Serial No. 245,681.

The present invention relates to improvements in wardrobe trunks wherein the wardrobe section of the trunk is provided with a plurality of garment hangers, pivotally connected at one end portion to a side wall of the said section, and further provided with a shelf for supporting the free end portions of the hangers while these are disposed in their normal positions within the section.

An object of the invention is the provision of means for preventing movement of the pivoted garment hangers while the trunk is closed and in transit. In this way crowding of the garments held by the carriers is prevented to the end that the garments are transported without acquiring undesirable folds or creases, or possible permanent damage.

The above and other objects will appear and be better understood from the following description:

The invention is defined in the claims.

A satisfactory embodiment of the invention is illustrated in the accompanying drawings in which

Figure 1 is a front elevation view of the interior upper portion of the wardrobe section of a wardrobe trunk showing the invention in use.

Figure 2 is a view on a slightly larger scale than Fig. 1, showing a detail plan of the invention.

Figure 3 is a side elevation of one end portion of the invention, and;

Figure 4 is a cross section approximately on the line 4-4 of Figure 2.

In the drawings A indicates generally the upper end portion of the wardrobe section of a conventional type of wardrobe trunk, the cover or companion section, which may or may not contain a plurality of drawers is not shown, since the same forms no part of the present invention. Such cover however will be regarded as being present in the finished trunk and hinged to one side of section A. The garment hanger 5 is of ordinary construction and connected at one end portion by a hinge 6 to a slide 7 mounted upon a carrier 8 which is connected by a hinge 9 to the outer portion of a side wall 10 of section A. In this connection it is to be understood that hanger 5 is one of a plurality of similar hangers which are individually mounted and slidable upon carrier 8. The said carrier by virtue of hinge 9 is turnable outwardly from the po-

sition shown in Fig. 1, and thereby operates to carry the hangers 5 bodily outward to a position in front of section A in which position the said hangers may be individually manipulated to turn and thereby afford easy access to any desired garment. The free end portions of the hangers are supported by a shelf 11 while the hangers are disposed within section A as shown in Fig. 1. Shelf 11 is disposed parallel with carrier 8, and rigidly secured to a side wall of section A opposite to carrier 8. As shown in Figure 4 shelf 11 is angular in cross section and disposed with one of its side portions in the horizontal in order to conveniently support the free end portions of hanger 5. A bayonet slot or angular sloped recess 12 extends transversely of the horizontally disposed side portion of shelf 11 the said recess extending thru the outer edge of the said side portion as shown in Fig. 2.

A keeper 13 is arranged to be moved into and out of recess 12, and across the path of movement of the hangers 5. The lower end portion of keeper 13 is pivoted as at 14 between a pair of horizontally extending arms 15-16 of a bracket, the base plate 17 of which is rigidly seamed as at 18 to the upright side portion 19 of shelf 11. A spring lock nut washer 20 is interposed between the arms 16 and a washer 21 on one side of keeper 13 and surround the pivot 14. This spring washer 20 operates to urge keeper 13 toward arm 15, and beyond one side of recess 12 as shown in Fig. 2.

From the foregoing it is evident that the tension of the spring washer 21 operated to hold keeper 13 against accidental turning movement. When the keeper is turned to the full line position shown in Fig. 1, washer 21 urges the keeper laterally and into the offset portion 21' of recess 12, and when the keeper is moved to the dotted line position of the said figure the tension of washer 21 moves the keeper to the position shown in Fig. 2. When the keeper is in the full line position shown in Fig. 1, the upper free end portion of the keeper bears upon the adjacent outermost hanger 5 so that outward movement of the said hanger and the carrier is positively prevented.

When the trunk is opened and the interior of section A exposed as shown in Fig. 1, keeper 13 may be readily manipulated to turn to

the dotted line position of the said figure whereupon the hangers and carrier may be swung outwardly.

From the foregoing it is obvious that the 5 device of the present invention is susceptible of various modifications and I reserve the right to the use of such of these as may come within the scope of the claims.

I claim:

- 10 1. In a wardrobe trunk, a garment hanger pivotally connected at one end to one side wall of the trunk; a shelf secured to an opposite side wall of the trunk and forming a support for the free end portion of the hanger, a keeper carried by the shelf and adjustable into and away from the path of movement of the hanger and a tensioned means for securing the keeper in any position of adjustment thereof.
- 15 2. In a wardrobe trunk, a garment hanger pivotally connected at one end to one side wall of the trunk, a shelf secured to an opposite side wall of the trunk and forming a support for the free end portion of the hanger, a keeper pivotally connected to the shelf and movable in one direction transversely of the shelf to intercept the free end of the hanger and further movable in an opposite direction and away from the hanger to permit
- 20 the same to be swung outwardly from the trunk and means operating by tension to yieldingly hold the keeper against movement.
- 25 3. In a wardrobe trunk, a pivoted garment hanger, a shelf forming a support for the

free end portion of the hanger and having a 35 transverse recess extending at an angle to the path of movement of the hanger, and a keeper pivotally connected to the shelf and movable into the recess to prevent movement of the hanger outwardly from the trunk. 40

4. In a wardrobe trunk a shelf forming a support for the free end portion of a garment hanger normally disposed transversely of the interior of the trunk and movable outwardly therefrom said shelf having angularly disposed side portions one of which is transversely recessed and a keeper pivotally connected to the other side portion of the shelf and movable into the recess to prevent 45 outward movement of the garment hanger. 50

5. In a wardrobe trunk a shelf forming a support for the free end portion of a garment hanger normally disposed transversely of the interior of the trunk and movable outwardly therefrom said shelf having angularly disposed side portions one of which is 55 provided with a transverse recess having an offset portion, a keeper pivotally connected to the other side portion of the shelf and movable into the offset portion of the recess to 60 prevent outward movement of the garment hanger and means operating to urge the keeper into the said offset portion of the recess. 65

In testimony whereof I have hereto affixed my signature on this 7th day of January, 1928.

ANTHONY J. TRENTACOSTE.
